UNITED STATES PATENT OFFICE

155,751

DESIGN FOR A BLOUSE OR SIMILAR ARTICLE

Victor Tomshinsky, New York, N. Y.

Application June 28, 1949, Serial No. 3,599

Term of patent 3½ years

(Cl. D3—25)

To all whom it may concern:

Be it known that I, Victor Tomshinsky, a citizen of the United States of America, residing in New York, county of New York, and State of New York, have invented a new, original, and ornamental Design for a Blouse or Similar Article, of which the following is a specification, reference being had to the accompanying drawing, forming part thereof.

Fig. 1 is a front view of a blouse or similar article, showing my new design.

Fig. 2 is a rear view thereof.

Fig. 3 is an enlarged fragmentary view of the front portion of the blouse, illustrating the collar portion in upturned position.

The design is characterized by the specific collar as shown on the drawing. The characteristic feature of my design resides in the portion shown in solid lines.

I claim:

The ornamental design for a blouse or similar article, substantially as shown and described.

VICTOR TOMSHINSKY.
